CAM LOCK SLIDER

George S. Malcolm, Harmonsburg, Pa., assignor to Talon, Inc., a corporation of Pennsylvania

Application June 8, 1953, Serial No. 360,280

10 Claims. (Cl. 24—205.14)

This invention relates to slide fasteners and, particularly to a new and improved slider therefor of the type illustrated and described in the United States Letters Patent to Carlile, No. 2,277,818, issued March 31, 1942.

In sliders of the type described in the above identified patent, the locking operation is performed manually by moving the pull tab down against the slider body to force into the fastener element guide channel of the slider, a somewhat yieldable locking tongue portion which is integral with the slider pull tab. When the pull tab is in its locked position this yieldable locking tongue rests upon or between the fastener elements in the slider channel and frictionally locks the slider against unintentional movement in a manner well known to those skilled in the art.

In sliders of this type of construction, usually this locking tongue portion extends above the slider body at least in one position of the pull tab member, i. e., when the pull tab is disposed in its extreme unlocked position. When the locking tongue is in positioned in such position above the slider body, it will be seen that it is exposed to any destructive force to which the slider may be subjected, such as that encountered in a pressing operation. That is, the locking tongue is liable to be bent inwardly when pressure is applied to it thereby making the slider no longer functional as a lock slider. It is to a slider having means incorporated therewith for protecting this yieldable locking tongue portion from bending and damage when pressure is applied to it that the present invention relates.

Accordingly, it is the general object of the present invention to provide a new and improved lock slider for slide fasteners of the type disclosed in the aforementioned patent having a safety feature incorporated to prevent damage to the locking portion when the slider is subjected to excessive pressure such as by pressing.

It is another object of this invention to provide an improved lock slider which is simple and inexpensive in its construction and, at the same time, a slider having increased strength over prior locking pull tab members of the same general type without in any way decreasing the efficient locking operation thereof.

Various other objects and advantages of this invention will be more apparent in the course of the following specification, and will be particularly pointed out in the appended claims.

In the accompanying drawings, there is shown for the purpose of illustration, an embodiment which my invention may assume in practice.

In these drawings:

Fig. 1 is a perspective view of the improved lock slider of the present invention showing the pull tab in locked position;

Fig. 2 is a perspective view similar to Fig. 1 showing the pull tab in its unlocked position;

Fig. 3 is a sectional view taken on line 3—3 of Fig. 1 with a fragmentary view of a portion of a fastener added;

2

Fig. 4 is a sectional view taken on line 4—4 of Fig. 2; Fig. 5 is a perspective view of the slider body in accordance with the present invention; and

Fig. 6 is a perspective view of the pull tab member.

5 Referring more particularly to the drawings, the improved slider of the present invention comprises a pair of spaced-apart overlying wing portions 2 and 3 integrally connected together at one end by a neck portion 4 and having marginal flange portions 5 so as to provide substantially a Y-shaped channel 6 between the wing portions. It will be understood that such a slider is assembled on the stringers of a conventional slide fastener (not shown) for longitudinal movement thereby for engaging and disengaging the fastener elements thereof in a manner well known to those skilled in the art.

According to the present invention, there is arranged in the upper wing portion 2 centrally thereof a rectangular-shaped aperture 7 which communicates with the slider channel 6 therein. There is arranged at opposite sides of this aperture 7, a pair of upwardly extending spaced-apart lugs 8 which are integrally connected together at the top thereof by a transversely extending bar-like portion 9 which bridges the aperture 7 substantially centrally thereof. These lugs 8 and the barlike portion 9 are preferably struck up from the material of the wing 2 so that they all overlie the aperture 7 therein.

There is provided a pull tab member 10 consisting of a plate-like body member having an arcuated yieldable tongue-like locking cam portion 12 arranged centrally 20 at one end thereof and which is disposed out of the plane of the body member. Also, at this end of this plate-like member there is arranged a pair of oppositely disposed trunnion portions 13 which extend inwardly and transversely and are arranged to either side of the tongue-like 25 locking portion 12 in substantially the plane of the body member.

This pull tab member 10 is hingedly connected to the slider body by means of the trunnion portions 13 which are loosely and pivotally disposed in under the respective 30 lugs 8. In such position, it will be seen that the tongue-like locking portion 12 is disposed directly opposite the transverse bar-like portion 9 extending between the lugs 8. It will also be seen that the centers of the arcuated tongue-like locking portion 12 and the bar-like transverse connecting portion 9 and the pivotal axes of the trunnion portions 13 are all disposed in substantially the same plane, as shown at line A—A in Fig. 4 of the drawings.

In one position of the pull tab 10, that is, when the pull tab is disposed in its extreme unlocked or upward position, as shown in Figs. 2 and 4, the tongue-like locking portion 12 thereof overlies and is disposed directly next to and around this bar-like connecting portion. It will be understood that it is the purpose of this transverse bar-like connecting portion 9 to lend support to the tongue-like portion 12 when the pull tab is disposed in such position, so as to prevent it from becoming deformed when excessive pressure is applied to the locking tongue and slider such as occurs in a pressing operation. In other words, this bar-like portion supports this tongue-like portion 12 and prevents it being bent downwardly between the lugs 8 when force is applied thereto so as to avoid the danger of destroying of the locking feature of the slider.

65 When it is desired to lock the slider, it will be understood that the pull tab 10 is manually operated and moved about its pivotal connection with the lugs 8 to a downward position substantially parallel to the slider wings, as shown in Figs. 1 and 3, whereby the locking tongue-like portion 12 is moved around to the underside of the bar-like portion 9 between the lugs 8 and passes into and through the aperture 7 and into engagement with the

fastener elements in the channel of the slider so as to lock the same against unintentional movement along the fastener in a well known manner.

As a result of my invention, it will be seen that there is provided a new and novel lock slider for slide fasteners which is strong and rugged in its construction having an extremely high resistance to damage by pressing because of the safety feature of the transverse bar-like lug connecting portion 9. By providing such a construction, it will be seen that the strength of the slider is substantially increased over prior locking pull tab members of the same general type without materially increasing the cost of manufacture thereof.

While I have shown and described one embodiment which my invention may assume in practice, it will be understood that this embodiment is merely for the purpose of illustration and description, and that other forms may be devised within the scope of my invention as defined in the appended claims.

What I claim as my invention is:

1. In a slider for slide fasteners, a slider body comprising a pair of overlying spaced-apart wing portions connected at one end by a neck portion so as to provide substantially a Y-shaped fastener element guide channel therebetween, one of said wings having an aperture therein substantially centrally thereof, a pair of pull tab retaining lugs arranged at opposite sides of said aperture laterally thereof, a locking pull tab member hingedly connected to said slider body comprising a plate-like member having a locking portion at one end adapted to project through said aperture into said channel and a pair of opposed trunnion portions extending inwardly and transversely and disposed beneath said lugs, and transversely extending means arranged integral with said lugs and bridging said aperture at a point directly opposite said locking portion, said locking portion positioned between said trunnion portions and being offset therefrom and adapted in one position of said pull member to extend around said transversely extending means whereby said locking portion is adapted to be supported and protected against destructive deformation upon application of destructive pressure to said locking portion and said pull tab.

2. In a slider for slide fasteners, a slider body comprising a pair of overlying spaced-apart wing portions connected at one end by a neck portion so as to provide substantially a Y-shaped fastener element guide channel therebetween, one of said wings having an aperture therein substantially centrally thereof, a pair of pull tab retaining lugs arranged at opposite sides of said aperture laterally thereof, a locking pull tab member hingedly connected to said slider body comprising a plate-like member having a locking portion at one end adapted to project through said aperture into said channel and a pair of opposed trunnion portions extending inwardly and transversely and disposed beneath said lugs, and a bar-like portion extending transversely between said lugs integrally connecting them together centrally thereof so as to bridge said aperture at a point directly opposite said locking portion, said locking portion positioned between said trunnion portions and being offset therefrom and adapted in one position of said pull member to extend around said transversely extending bar-like portion whereby said locking portion is adapted to be supported and protected against destructive deformation upon application of destructive pressure to said locking portion and said pull tab.

3. In a slider for slide fasteners, a slider body comprising a pair of overlying spaced-apart wing portions connected at one end by a neck portion so as to provide substantially a Y-shaped fastener element guide channel therebetween, one of said wings having an aperture therein substantially centrally thereof, a pair of pull tab retaining lugs arranged at opposite sides of said aperture laterally thereof, a locking pull tab member hingedly con-

nected to said slider body comprising a plate-like member having an arcuated yieldable locking tongue-like portion at one end adapted to project through said aperture into said channel and a pair of opposed trunnion portions extending inwardly and transversely and disposed beneath said lugs, and transversely extending means arranged integral with said lugs and bridging said aperture at a point directly opposite said tongue-like locking portion, said tongue-like locking portion positioned between said trunnion portions and being offset therefrom and adapted in one position of said pull member to extend around said transversely extending means whereby said locking portion is adapted to be supported and protected against destructive deformation upon application of destructive pressure to said locking portion and said pull tab.

4. In a slider for slide fasteners, a slider body comprising a pair of overlying spaced-apart wing portions connected at one end by a neck portion so as to provide substantially a Y-shaped fastener element guide channel therebetween, one of said wings having an aperture therein substantially centrally thereof, a pair of pull tab retaining lugs arranged at opposite sides of said aperture laterally thereof, a locking pull tab member hingedly connected to said slider body comprising a plate-like member having an arcuated yieldable locking tongue-like portion at one end thereof adapted to project through said aperture into said channel and a pair of opposed trunnion portions extending inwardly and transversely therefrom and disposed beneath said lugs to either side of said locking portion, and a bar-like transverse portion extending between said lugs integrally connecting them together centrally thereof so as to bridge said aperture at a point directly opposite said locking portion, said arcuated tongue-like locking portion positioned between said trunnion portions and being offset therefrom and being disposed and movable around said transverse portion whereby said locking portion is adapted to be supported and protected against destructive deformation upon application of destructive pressure to said locking portion and said pull tab.

5. In a slider for slide fasteners, the combination as defined in claim 4, wherein the centers of the arcuated tongue-like locking portion and the bar-like transverse connecting portion and the pivotal axes of the trunnion portions are all disposed in substantially the same plane.

6. In a slider for slide fasteners, a slider body comprising a pair of overlying spaced-apart wing portions connected at one end by a neck portion so as to provide substantially a Y-shaped fastener element guide channel therebetween, one of said wings having an aperture therein substantially centrally thereof, a pair of pull tab retaining lugs arranged at opposite sides of said aperture laterally thereof, a locking pull tab member hingedly connected to said slider body comprising a plate-like member having an arcuated yieldable locking tongue-like portion arranged centrally at one end thereof and disposed out of the plane of the body portion of said tab member and which is adapted to be disposed in one position of said tab member in said aperture and extend into said channel and a pair of opposed trunnion portions extending inwardly and transversely and disposed beneath said lugs, said trunnion portions disposed substantially in the plane of the body portion of said tab member to either side of said locking portion, and a bar-like transverse portion extending between said lugs centrally thereof integrally connecting them together at the top thereof and bridging said aperture at a point directly opposite said locking portion, said arcuated tongue-like portion positioned between said trunnion portions and being offset therefrom, said arcuated tongue-like locking portion adapted to lie over and substantially next to said transverse portion when the pull tab is disposed in its unlocked position substantially parallel to the slider wings whereby said locking portion is adapted to be supported and protected against destructive deformation by said trans-

verse portion upon application of destructive pressure to said locking portion and said pull tab.

7. In a slider for slide fasteners, the combination as defined in claim 6, wherein the centers of the arcuated tongue-like locking portion and the bar-like transverse connecting portion and the pivotal axes of the trunnion portions are all disposed in substantially the same plane.

8. In a slider for slide fasteners, a slider body comprising a pair of overlying spaced-apart wing portions connected at one end by a neck portion so as to provide substantially a Y-shaped channel therebetween, one of said wings having an aperture therein substantially centrally thereof, a pull tab member, a lug-like portion including transversely extending means bridging said aperture, said lug-like portion being open to either side thereof to which said pull tab member is hingedly connected to either side of said aperture by means of a pair of opposed trunnion portions disposed in said openings, and a cam-like locking prong carried by said pull tab at one end thereof, said cam-like locking prong positioned between said trunnion portions and being offset therefrom, said locking prong disposed around said bridging means and adapted to extend through said aperture into said slider channel when said pull tab is disposed in one position and adapted to be disposed over said bridging means on the outer side thereof when said pull tab is disposed in another position.

9. In a slider for slide fasteners, a slider body comprising a pair of overlying spaced-apart wing portions connected at one end by a neck portion so as to provide substantially a Y-shaped channel therebetween, one of said wings having an aperture therein substantially centrally thereof, a pull tab member, a lug-like portion including transversely extending means bridging said aperture, said lug-like portion being open to either side thereof to which said pull tab member is hingedly connected to either side of said aperture by means of a pair of opposed trunnion portions disposed in said openings, and an arcuated yieldable cam-like locking tongue carried by said pull tab at one end thereof which is disposed out of the

plane of the body portion of said pull tab, said cam-like locking tongue positioned between said trunnion portions and being offset therefrom, said locking tongue disposed around said bridging means and adapted to extend through said aperture into said slider channel in under said bridging means when said pull tab is disposed in one position, and adapted to be disposed over said bridging means on the outer side thereof when said pull tab is disposed in another position.

10. In a slider for slide fasteners, a slider body comprising a pair of overlying spaced-apart wing portions connected at one end by a neck portion so as to provide substantially a Y-shaped fastener element guide channel therebetween, one of said wings having an aperture therein substantially centrally thereof, a pair of pull tab retaining lugs arranged at opposite sides of said aperture laterally thereof, a pull tab member having a pair of spaced-apart opposed trunnion portions arranged at one end thereof, said trunnion portions positioned beneath said lugs so as to be hingedly connected to the slider body, an outwardly extending arcuated cam-like locking portion carried by said pull member and positioned between said trunnion portions and out of the plane thereof, and a bar-like portion extending between said lugs and bridging said aperture at a point directly opposite said cam-like locking portion, said cam-like locking portion adapted to extend into said aperture and the slider channel in under the bar-like portion when said pull tab is disposed in its locked position, and adapted to be disposed over said bar-like portion on the outer side thereof when said pull tab is disposed in its unlocked position.
